HANDBAG

Ludwig S. Schlessinger, New York, N. Y.

Application January 24, 1950, Serial No. 7,448

Term of patent 7 years

(Cl. D87—3)

To all whom it may concern:

Be it known that I, Ludwig S. Schlessinger, a citizen of the United States of America, residing in the city of New York, county of New York, State of New York, have invented a new, original, and ornamental Design for a Handbag, of which the following is a specification, reference being had to the accompanying drawings, forming a part thereof, wherein:

Fig. 1 is a perspective view of a handbag embodying my new design, illustrating one end of the closure member unsnapped; and

Fig. 2 is an end elevation of the handbag.

The dominant features of my design are shown in full lines.

I claim:

The ornamental design for a handbag, substantially as shown and described.

LUDWIG S. SCHLESSINGER.
